CLAIM

The ornamental design for triple header key holder, as shown and described.

DESCRIPTION

FIG. 1 is a front perspective view of a triple header key holder in inverted position showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and

FIG. 8 is a front perspective view of a modified form of a triple header key holder from that shown in FIG. 1 in inverted position;

FIG. 9 is a front elevational view of FIG. 8;

FIG. 10 is a rear elevational view of FIG. 8;

FIG. 11 is a left side elevational view of FIG. 8;

FIG. 12 is a right side elevational view of FIG. 8;

FIG. 13 is a top plan view of FIG. 8; and,

FIG. 14 is a bottom plan view of FIG. 8.

The broken line showings of key rings are for illustrative purposes and form no part of the claimed design.
